UNITED STATES PATENT OFFICE

JAMES R. CLARK, OF WALHALLA, SOUTH CAROLINA, ASSIGNOR TO KENNETH COTTON MILLS, OF WALHALLA, SOUTH CAROLINA, A CORPORATION OF SOUTH CAROLINA

DESIGN FOR A BEDSPREAD OR SIMILAR ARTICLE

Application filed July 1, 1930. Serial No. 36,250. Term of patent 3½ years.

To all whom it may concern:

Be it known that I, JAMES R. CLARK, a citizen of the United States, residing at Walhalla, in the county of Oconee and State of South Carolina, have invented a new, original, and ornamental Design for a Bedspread or Similar Article, of which the following is a specification, reference being had to the accompanying drawing, forming part thereof.

The drawing is a plan view of a bed spread with the central portion omitted and the surface design incompletely illustrated, but intended to be repeated in the relation shown on the lower left hand fragmentary portion of the disclosure of the drawing.

I claim:—

The ornamental design for a bed spread or similar article, as shown, and described.

JAMES R. CLARK.
